Inventor:

Joseph Francis Quigley

*Victor J. Evans,
ATTORNEY*

UNITED STATES PATENT OFFICE.

JOSEPH FRANCIS QUIGLEY, OF OKLAHOMA CITY, OKLAHOMA.

CLOTHESLINE TIGHTENER.

Application filed October 19, 1928. Serial No. 313,540.

This invention relates to clothes lines and its general object is to provide a clothes line with means for drawing the same taut in an easy and expeditious manner with very little effort.

Another object of the invention is to provide a tightener for clothes lines, to prevent sagging thereof with the result the use of props, and the like will be eliminated.

10 A still further object of the invention is to provide a clothes line with tightening means therefor, that is extremely simple in construction, inexpensive to manufacture and efficient in operation and service.

15 This invention also consists in certain other features of construction and in the combination and arrangement of the several parts, to be hereinafter fully described, illustrated in the accompanying drawings 20 and specifically pointed out in the appended claims.

In describing my invention in detail, reference will be had to the accompanying drawings wherein like characters denote like 25 or corresponding parts throughout the several views, and in which:

Figure 1 is a fragmentary front elevation illustrating the clothes line and its tightening means which forms the subject matter of 30 the present invention applied to posts.

Figure 2 is a sectional view illustrating the turn buckle of my tightening means.

Figure 3 is a view taken at right angles to one of the posts shown in Figure 1 and 35 illustrates the manner of countersinking the nuts therein.

Figure 4 is a fragmentary view of a fastener to be used on buildings and the like.

Referring to the drawings in detail the 40 reference numeral 1 indicates a pair of posts which are supported in an upright position in any suitable manner and have arranged adjacent their upper ends transversely disposed bores for a purpose which will be presently apparent.

Disposed in the bore of one of the posts is the shank 2 of a fastening element which includes an eye 3 formed on one end and the shank 2 is threaded to accommodate a nut 4 45 that is countersunk in the post so as to prevent turning of the shank as will be apparent.

Secured to the eye is one of the ends of a flexible element 5 which constitutes the 50 line for receiving clothes and this flexible

element may be wire, rope or other like means.

The opposite end of the flexible element 5 is secured to an eye 6 that is formed on one of the ends of a threaded shank 7, and 60 the eye 6 has formed therewith a handle 8 arranged at right angles with respect to the threaded shank 7 which is threadedly secured in an opening formed in the enlarged central portion 9 of one of the end members 65 of a frame, and this frame is in the form of a turn buckle and not only includes the end member referred to and which is indicated by the reference numeral 10 but also includes longitudinally arranged spaced parallel members 11 and an end member 12 having an enlarged central portion with a threaded opening formed therein to threadedly receive a threaded bolt 13 that is passed through the bore of the other post and is 70 held therein through the instrumentality of a nut 14 that is likewise countersunk in the post as shown.

The end member 10 is relatively longer than the end member 12 so as to provide 80 handles for operating the tightener which includes the elements just described and is clearly shown in Figure 1 of the drawings.

In Figure 4, I have illustrated a fastening means to be used on buildings and the like, 85 where there is no available space for burying or supporting posts such as indicated by the reference numeral 1 and this fastener includes a base plate 15 having openings formed therein to accommodate screws 16 90 for securing the fastener to a building and extending centrally from the base plate 15 is the shank 17 of a hook 18 which of course is adapted to receive one of the ends of the flexible element 5 while its opposite end is 95 fixed to the eye 6 of the tightener, the tightener being secured to the side of a building in any appropriate manner as will be apparent.

It is thought from the foregoing description that the advantages and novel features of my invention will be readily apparent.

I desire it to be understood that I may make changes in the construction and in the combination and arrangement of the several 105 parts, provided that such changes fall within the scope of the appended claims.

What I claim is:

1. A clothes line organization comprising 110 a flexible element, means securely receiving

- one of the ends of said flexible element, tightening means including an eye securely receiving the opposite end thereof, a handle formed with said eye, a threaded shank formed with said eye and a turn buckle threadedly receiving said threaded shank.
2. A clothes line organization comprising a flexible element, means for securely receiving one of the ends of said flexible element, a tightener including an eye securely receiving the opposite end of said flexible element, a handle formed with said eye, a threaded shank formed with said eye and being disposed at right angles with respect to said handle, a turn buckle including end members having threaded openings formed therein, the threaded opening of one of said end members threadedly receiving the threaded shank, handles formed on the last mentioned end member and cooperating with the handle first mentioned, means threadedly received in the opening of the other end member and securing means for the last mentioned means.
3. A clothes line tightener comprising a frame in the form of a turn buckle and including longitudinally arranged spaced parallel members, end members formed with said parallel members and being provided with enlarged portions formed with threaded openings, a threaded bolt received in the threaded opening of one of said end members, a shank received in the opening of the other end member, an eye formed with said shank, a handle formed with said shank at right angles to the threaded shank, and one of said end members being longer than the other to provide handles.

In testimony whereof I affix my signature.
JOSEPH FRANCIS QUIGLEY.
